CASE FOR A PENDANT WATCH OR THE LIKE

Pirmin Ochs, Pforzheim, Germany, assignor to Rodi & Wienenberger Aktiengesellschaft, Pforzheim, Germany

Filed Sept. 8, 1970, Ser. No. 24,859

Claims priority, application Germany July 3, 1970

Term of patent 3½ years

Int. Cl. D10—02

U.S. Cl. D42—8

FIG. 1

FIG. 2

FIG. 1 is a front elevational view of a case for a pendant watch or the like showing my new design;

FIG. 2 is a bottom edge elevational view.

The rear view of the case for a pendant watch or the like not shown in the drawing has an appearance identical with the appearance of the front view shown in FIG. 1 of the drawing.

I claim:

The ornamental design for a case for a pendant watch or the like, substantially as shown and described.
